UNITED STATES PATENT OFFICE.

JOHN T. MORGAN, OF CHARLESTON, WEST VIRGINIA, ASSIGNEE TO THE OHIO BRASS COMPANY, OF MANSFIELD, OHIO, A CORPORATION OF NEW JERSEY.

SECTIONAL INSULATOR.

1,354,505.

Specification of Letters Patent.

Patented Oct. 5, 1920.

Application filed May 24, 1919. Serial No. 299,667.

To all whom it may concern:

Be it known that I, JOHN T. MORGAN, a citizen of the United States, now in France with the American Expeditionary Forces, 5 and who resides at Charleston, in the county of Kanawha and State of West Virginia, have invented certain new and useful Improvements in Sectional Insulators, of which the following is a specification.

10 This invention relates to improvements in section insulators and has more particular reference to the type of section insulator switches used most generally in mines and similar places.

15 One object of my invention is to provide an improved device of this character which will be simple, durable and reliable in construction and effective and efficient in operation.

20 Another object is to provide improved means for maintaining the switch in open position.

25 A further object is to provide a device of the character referred to, having improved means whereby it may be readily and conveniently secured in or removed from operative position.

30 A still further object is to produce an improved section insulator switch having means whereby a substantially continuous or unobstructed under-run surface is provided in either open or closed positions of the switch for engagement with the collectors of cars when passing thereunder.

35 To the attainment of these ends and the accomplishment of other new and useful objects, as will appear, the invention consists in the features of novelty in the construction, combination and arrangement of 40 the several parts to be hereinafter more fully described and claimed and shown in the accompanying drawings illustrating one embodiment of the invention, and in which:

45 Figure 1 is a side view of a section insulator switch embodying my invention and in which the switch is shown as closed.

Fig. 2 is a bottom plan view thereof.

50 Fig. 3 is a longitudinal, horizontal section on the line 3—3 of Fig. 1, and in which the switch is shown as open.

Fig. 4 is a transverse section on the line 4—4 of Fig. 1.

Fig. 5 is a transverse section on the line 5—5 of Fig. 1.

In the drawings the same reference characters indicate the same parts throughout the several views.

Referring to the drawings which illustrate the embodiment of the preferred form of my invention, metallic end members 1 and 2 are shown as secured to a bar 3, composed of insulation material, by means of bolts 4 passing through suitable apertures 65 formed in the bar and having threaded engagement with the end members. The end members are provided with runner pieces 5 and 6 preferably formed integral therewith and which project beyond the ends of 70 the bar 3 and have their lower edges rounded similar to the shape of a trolley wire so as to form a smooth under-run surface for the collector of cars when passing thereunder. The outer ends of the runners are 75 provided with suitable openings to receive the adjacent ends of two conductors 7 and 8 which may be secured therein in any suitable or approved manner, such for instance as by means of set screws 9. The end members are provided with lug projections 10 adjacent the ends of the bar 3, which projections have transverse holes 11, and set screws 12, for the purpose of attaching 80 feeder wires to the device.

85 The inner ends of the end members are spaced apart forming a considerable gap therebetween and for the purpose of substantially closing this gap in order to provide a more nearly continuous or uninterrupted surface to coöperate with the collectors of cars, and to eliminate hammering I provide an intermediate stationary runner-piece 13 having its under edge rounded off 90 similar to the end members 1 and 2 and 95 flush with the under-run surfaces thereof. This stationary runner piece is interposed between the inner ends of the end members and substantially bridges the gap therebetween, being of such a length as to provide 100 spaces 14 between the parts of sufficient dimensions to prevent sparking or leakage of current across the end members when the device is in open position in which position the end members are electrically disconnected, as will be described hereinafter.

For the purpose of rigidly securing the in-

termediate runner piece 13 in position I preferably provide a bracket 15 secured to the bar 3 by clamping bolts 16 said bracket having a suitable aperture adapted to receive the connecting bolt 17 which is threaded into the runner piece 13 and interlocked therewith against accidental disengagement by means of a transverse pin 18, as clearly shown in Fig. 4. The bracket 15 and the stationary runner piece 13 comprise flanges 19 and 20 respectively at their adjacent ends which are maintained in spaced relation, forming a space 21 therebetween, by means of lugs 22 preferably formed integrally with the flange 20. These lugs are apertured to receive screws 23 which are threaded into the bracket 15 and which serve to interlock the stationary runner piece 13 against rotation with the bracket.

20 In order to provide for electrically connecting the end members 1 and 2 I arrange a switch blade 24 in the space 21. This switch blade has a central hole through which the connecting bolt 17 passes and it is free to rotate about this bolt and its ends are adapted to enter between and engage stationary clips or contacts 25 preferably in the form of flat pieces of metal having their inner ends 26 secured in grooves formed in the end pieces 1 and 2 and which are locked in position by transverse pins 27. The switch blade and its co-acting clips are positioned above the path of movement of the trolley collector wheel, not shown, so that there is no danger of damage therefrom.

A handle 28 is provided for operating the switch blade 24. One end of this handle is secured to an integral projection 29 outstanding laterally from a filler block 30 secured to the switch blade by means of a screw 31. Another filler block 32 is arranged on the switch blade and is secured thereto in spaced relation with the filler block 30 by means of a screw 33. This filler block comprises a lateral extension 34 provided with an opening by means of which one end of a tension spring 35 is secured thereto. The other end of the spring 35 may be connected to the bar 3 in any suitable or approved manner, such for instance as by means of a screw eye 36. This spring serves to maintain the switch blade in engagement with the lugs 23, (see Fig. 3) when the device is in open position and operates to prevent accidental closing of the switch, as by jarring. The filler blocks 30 and 32 have their under edges rounded off similar to the end runners and are arranged and adapted to be positioned within and fill the spaces 14 when the device is in closed position and form in conjunction with the end runners and the stationary runner piece a mechanically continuous or uninterrupted under-run surface, as clearly shown in Figs. 1 and 2.

65 When the switch blade 24 is operated into

engagement with its co-acting clips or contacts 25 sufficient friction is obtained between the parts to resist action of the spring 35 which is then maintained in extended position.

To support the device and hold it in position I preferably provide two clevises 37 which embrace the bar 3 and are secured thereto, one adjacent each end thereof, by means of transverse bolts 38. These clevises 75 have studs 39 rigidly secured therein, as by riveting, as shown, or otherwise, which studs are screw threaded, preferably left-handed, for engagement with the similarly threaded ends of adjusting collars 40. The adjusting 80 collars 40 may be provided with polygonal sided portions 41 and have their opposite ends screw threaded, preferably right-handed, for engagement with the studs 42 of any suitable hangers or supports 43.

In practice when it is desired to secure the device in position the operator first partially unscrews or removes the adjusting collars 40 from the studs 39 within a short distance of their ends, by rotating the adjusting collar in one direction. The device is then arranged into position by bringing the free ends of the adjusting collars 40 into engagement with the ends of the studs 42 and is then secured to the hangers or supports by 95 rotating the collars 40 in the opposite direction. This rotation of the adjusting collars causes them to engage or screw onto the threads of the studs 39 and 42 simultaneously, by reason of said threads being one 100 right-handed and the other left-handed, as above stated, and is continued until the upper end surface of the adjusting collar is brought into engagement with the lower surface of the support, as shown in Fig. 1. 105 It will be noted that this arrangement provides for rigidly securing the device in position.

Having thus fully described my invention and illustrated one embodiment of the same, I do not wish to be limited to the details of the construction shown since these can be obviously changed without departing from the spirit of this invention.

I claim as my invention:

1. In a device of the class described, the combination of a bar of insulating material, a pair of terminal members spaced apart and secured to the bar, a stationary member forming an under-run supported by the bar and interposed between the terminal members and spaced therefrom, a rotatable filler member arranged to be moved into alignment with said terminal and stationary members to complete the under-run 120 from terminal to terminal, means for electrically connecting the terminal members when the rotatable filler member is moved into alignment, and means for rotating the filler member and the electrical connecting 125 130

- means in and out of position with the terminal members.
2. In a device of the class described, the combination of a supporting member and terminal members insulated therefrom and spaced apart, a stationary underrun member interposed between said members and in alinement therewith, a rotatable switch blade, filler blocks carried by the switch blade and arranged to be moved into alinement with said terminal members and said stationary member, and contacts on said terminal members adapted to be engaged by the switch blade to electrically connect said terminal members when said filler members are moved to aligned positions.
3. In a device of the character described, the combination of a bar of insulating material and end members attached thereto adjacent the ends thereof and to which a trolley wire is adapted to be attached, a stationary underrun member mounted on said bar between said end members and in alinement therewith, a rotatable switch blade, a plurality of filler blocks carried by said switch blade and arranged to be moved intermediate the adjacent ends of said end members and said stationary underrun member and to be positioned in alinement therewith to form a mechanical continuation thereof, and contacts engageable by said switch blade mounted on said end members.
4. In a device of the class described, the combination of a bar of insulating material and end members attached to said bar adjacent the ends thereof and to which a trolley wire is adapted to be attached, a stationary underrun member secured to said bar between said end members and in alinement therewith, a rotary switch blade, filler blocks mounted on said switch blade and rotatable therewith and adapted to be positioned intermediate the adjacent ends of said end members and said stationary underrun member to form a mechanical continuation thereof, contacts engageable by said switch blade mounted on said end members, and a handle outstanding from said switch blade for rotating it and the filler blocks.
5. An insulator of the class described having in combination a plurality of alternately placed terminal and intermediate members spaced apart and insulated from each other and forming a partial underrun for a moving current collector and means adapted to be moved in and out of alinement with the above members to complete or interrupt the continuity of the underrun and means secured to the last mentioned means to electrically connect or disconnect the alternately placed members when the last means is moved in and out of alinement with the alternately placed pair of members.

6. In a device of the class described, the combination of a bar of insulating material and end members attached thereto in alinement with each other and spaced apart, a stationary underrun member secured to the bar between the end members and in alinement therewith, a rotary switch blade, contacts engageable by said switch blade mounted on said end members, filler blocks carried by the switch blade and rotatable therewith and adapted to be positioned intermediate the adjacent ends of said end members and said stationary underrun member to form a substantially continuous underrun surface from one of said members to the other when the switch blade is in engagement with the contacts, a handle for rotating the switch blade, and means for securing the device to a support.
7. In a device of the class described, the combination of a horizontally disposed bar of insulating material, end members mounted thereon in substantial alinement therewith and spaced apart, a bracket secured to said bar, a stationary underrun member secured to the bracket between the end members and in alinement therewith, a holding device for securing the stationary underrun member to the bracket, a switch blade rotatable about said holding device for electrically connecting the end members, filler blocks carried by said switch blade and arranged to be positioned intermediate the adjacent ends of said end members and said stationary underrun member to form a continuous underrun surface from end to end of the device, contacts engageable by the switch blade secured to the end members, a handle for the switch blade, and attaching means secured to said bar adjacent each end thereof.
8. In a device of the character described, the combination of a bar of insulating material and end members attached thereto adjacent the ends thereof, a bracket secured to the bar, a stationary underrun member secured to the bracket between the inner ends of the end members and in alinement therewith, a switch blade rotatably mounted between the bracket and said underrun member for electrically connecting the end members, filler blocks carried by the switch blade and arranged to be positioned between the ends of said stationary underrun member and the adjacent ends of the end members to form a continuous underrun surface from one end member to the other, contacts engageable by the switch blade secured to the end members, a handle for the switch blade, a spring having one end connected to the switch blade and its other end connected to said bar for maintaining the switch blade out of engagement with the contacts, and means for securing the device to a support.

9. In a device of the character described, the combination of a bar of insulating material and end members attached thereto and spaced apart, a stationary underrun member secured to the bar between the end members and in alinement therewith, a switch blade for electrically connecting the end members, filler blocks arranged to be positioned between the ends of the end members and the adjacent ends of the stationary underrun member, means for operating the switch blade, and means for removably securing the device to a support.

10. In a device of the class described, the combination of a horizontally disposed bar of insulating material, end members mounted thereon in substantial alinement therewith and spaced apart, a bracket fastened to the bar, a nonrotatable underrun member secured to the bracket between the end members in alinement therewith and spaced apart, contact clips mounted on said end members adjacent their inner ends, a switch blade movable into engagement with said clips for electrically connecting the end members, filler blocks rotatable into alinement with said end members and underrun member to mechanically bridge the spaces therebetween, means for actuating the switch blade and filler block, and fastening means on said device for attachment to supporting means.

11. In a device of the class described, the combination of a horizontally disposed bar of insulating material, and members spaced apart and secured to the under edge of said bar adjacent the ends thereof and in substantial alinement therewith, runner pieces

formed on said end members and projecting beyond and in alinement therewith for attachment to the trolley wire ends, a non-rotatable underrun member secured to the bar between the end members and in alinement therewith and having its ends terminating in spaced relation with the adjacent ends of the end members forming gaps therebetween, a switch blade operable to electrically connect and disconnect said end members, means to operate the blade into and out of engagement with one member, 50 filler blocks movable into said gaps to mechanically bridge the spaces between the adjacent ends of the end members and said underrun member and means to operate the filler block into and out of alinement with the end members.

12. In a device of the class described the combination of a bar of insulating material, a plurality of terminal members spaced apart and insulated from each other, a 60 switch adapted to electrically connect and disconnect the terminal members, means secured to the switch member and movable therewith in and out of alinement with the terminal members to form an under-run for 65 a current collector when the switch is open, and a stationary under-run member supported by the insulating bar and interposed between and insulated from the terminal members and forming an under-run for the 70 current collector when the switch is open and the means secured to the switch is out of alinement with the terminal members.

In testimony whereof I affix my signature.

JOHN T. MORGAN.
